UNITED STATES PATENT OFFICE.

JOHN C. DONOVAN AND FRANK J. LONG, OF DUBUQUE, IOWA, ASSIGNOR TO HAWKEYE CASKET COMPANY, OF DUBUQUE, IOWA, A CORPORATION OF IOWA.

DESIGN FOR A RADIO CONSOLE CABINET.

Application filed March 23, 1925. Serial No. 12,815. Term of patent 7 years.

To all whom it may concern:

Be it known that we, JOHN C. DONOVAN and FRANK J. LONG, citizens of the United States, residing at Dubuque, in the county of Dubuque and State of Iowa, have invented a new, original, and ornamental Design for a Radio Console Cabinet, of which the following is a specification, reference being had to the accompanying drawing, forming part thereof.

Figure 1 is a perspective view of a console cabinet showing our new design, and Figure 2 is a horizontal section thereof.

We claim:

The ornamental design for a radio console cabinet as shown.

JOHN C. DONOVAN.
FRANK J. LONG.
